UNITED STATES PATENT OFFICE.

PAUL WERNER, OF ST. LOUIS, MISSOURI.

CAN OPENER.

Application filed November 22, 1926. Serial No. 149,939.

This invention relates to a certain new and useful improvement in can-openers and has for its object the provision of a device or tool of the type stated that is simple, inexpensive, and compact in form and construction, which is conveniently manually operable, and which is efficient in the performance of its intended functions.

And with the above and other objects in view, my invention resides in the novel features of form, construction, arrangement, and combination of parts hereinafter described and pointed out in the claims.

In the accompanying drawing,

Figure 1 is a transverse sectional view, in cutting position upon a can, fragmentally shown, of a can-opener embodying my invention;

Figure 2 is a plan view of the can-opener; and

Figure 3 is a fragmental plan view of a slightly modified form of can-opener embodying my invention.

Referring now more in detail and by reference characters to the drawing, my new can-opener includes a body-member constructed of suitable metallic material and in the form of a plate 1 preferably of generally or approximately circular contour, as best seen in Figure 2. Preferably, further, as shown, the plate 1 is formed or provided continuously throughout its margin with a lateral flange 2.

Formed or provided radially in plate 1, is a closed-end slot 3, and adapted for adjustable movement in slot 3, in a preferably threaded pin or stem 4 of a depending member or enlargement 5 arcuated transversely relatively to slot 3 for can-gripping or engagement in co-operation with the opposed portion of flange 2, and having threaded engagement with stem 4 for impinglying engaging the plate 1 for releasably retaining the stem 4 and its depending can-gripping member 5 in relatively adjusted position, is a knob 6, which is adapted to also function as a manual gripping-member for the can-opener in facilitating can opening or cutting operations.

Adapted for co-operation with the plate 1 in can-cutting operations, is a suitable preferably renewable blade which may, as shown in Figures 1 and 2, be of angular formation in side elevation, integrally including a flat shank 7 and a down-turned flat end or cutting-portion 8, or, as shown

in Figure 3, be in the form of a disk 9 having a hub-portion 10. In one instance, the plate 1, preferably in radial alignment with, and opposite the inner end of, the slot 3, is formed or provided with a blade-seat in the form of a pair of spaced relatively flat transversely disposed rigid straps 11 for slidably accommodating and engaging with the flat shank 7 of the blade, the plate 1 with its flange 2 being cut away or recessed upon its margin, as at 12, for accommodating the depending end-portion 8 of the blade. In the other instance, the plate 1 with its flange 2 is cut-away or recessed upon its margin, as at 13, for accommodating the disk-blade 9 and its hub 10, and formed or provided with a blade-seat preferably in the form of a suitably elongated semi-cylindrical strap 14 for slidably accommodating the shank of the blade which is in the form of a stub shaft 15, which latter is projected through the disk 9 and its hub 10 and into the seat 14 and which provides a supporting shaft for the blade. In both instances, as will be noted, while the respective blades are firmly supported and carried by the plate 1 for can-cutting operations, without the necessity of the employment of any additional members or means, both types of blades are readily removable or detachable from the plate for such repair or replacement as may become necessary.

In use or operation, the plate 1 is disposed flatwise upon the can C whose end-wall 16 is to be cut, and the blade-portion 8 or disk 9, as the case may be, forcibly driven into the wall 16 under suitable pressure applied upon the plate 1. The can-gripping member 5 is then, by proper manipulation of the knob 6, suitably adjusted to grip the can C at a point diametrically opposite the blade. Then, with the knob 6 preferably gripped between the thumb and first finger and the plate gripped at its margin by the tips of the fingers, the blade is manually rotatorily moved bodily upon and relatively to the can and the blade consequently shifted around the margin of the can. Such operation effects a clean cut of the can-wall 16, without any remaining ragged edges in the cut can.

In such operations, the flange 2 of the plate 1 facilitates gripping engagement by the hand with the plate, and both the plate 1 and its flange 2 prevent the splashing or spouting from the can of any contained liquid or other contents. Preferably the

can-gripping member 5 is formed with an inwardly presented projection 5^a for facilitating firm engagement between the member 5 and the bead of the can.

My new can-opener may be used with safety and convenience in the cutting of lids from either hot or cold cans, is readily and easily manipulated in cutting operations, and has been found exceedingly efficient in the performance of its intended functions.

I am aware that changes in the form, construction, arrangement, and combination of the several parts of my new can-opener may be made and substituted for those herein shown and described without departing from the nature and principle of my invention.

Having thus described my new invention, what I claim and desire to secure by Letters Patent is:

1. A can-opener including a plate having a laterally flanged portion, a cutting-blade carried by the plate and located adjacent

the margin of the plate, the plate being adapted for bodily disposition and movement flatwise upon a can for shifting the blade in can-cutting operations, and means carried by the plate for co-operation with said flanged portion in adjustably adapting the can-opener for engagement with cans of different diameters. 25

2. A can-opener including a plate having a radial slot and a laterally flanged portion, a cutting-blade carried by the plate and located adjacent the margin of the plate, the plate being adapted for bodily disposition and movement flatwise upon a can for shifting the blade in can-cutting operations, and means including an arcuate member having a stem working in said slot for co-operation with said flanged portion in adjustably adapting the can-opener for engagement with cans of different diameters. 30 35

In testimony whereof, I have hereunto signed my name to this specification.

PAUL WERNER.
